(57) **CLAIM**

The ornamental design for a griddle, as shown and described.

DESCRIPTION

FIG. 1 is a perspective view as seen from the top, front and left side of a griddle showing our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof;

FIG. 7 is a bottom plan view thereof;

FIG. 8 is a perspective view as seen from the top, front and left side of a second embodiment of the griddle showing our new design;

FIG. 9 is a front elevational view thereof;

FIG. 10 is a right side elevational view thereof;

FIG. 11 is a left side elevational view thereof;

FIG. 12 is a rear elevational view thereof;

FIG. 13 is a top plan view thereof; and,

FIG. 14 is a bottom plan view thereof.

The broken lines in FIGS. 2, 3, 4, 5 and 8 showing the feet and the underside of the griddle are used for illustrative purposes only and form no part of the claimed design.

The broken lines in FIGS. 8 through 14 showing the feet, the dial slot and knob of the griddle, the power indicator light, and the underside of the griddle are used for illustrative purposes only and form no part of the claimed design.

1 Claim, 2 Drawing Sheets
